CLAIM

The ornamental design for a casement window folding handle and cover, as shown and described.

DESCRIPTION

FIG. 1 is a perspective view of a casement window folding handle and cover showing our new design;

FIG. 2 is a front elevational view thereof;

FIG. 3 is a rear elevational view thereof;

FIG. 4 is a top plan view thereof;

FIG. 5 is a left side elevational view thereof; and,

FIG. 6 is a right side elevational view thereof.

The broken lines, which define the bounds of the claimed design, form no part thereof. Other broken lines are for illustrative purpose only and form no part of the claimed design. The bottom of the design disclaimed.
